UNITED STATES PATENT OFFICE.

WILLIAM F. SHAW, OF PUEBLO, COLORADO.

ARTIFICIAL-TOOTH ATTACHMENT.

1,301,181.

Specification of Letters Patent. Patented Apr. 22, 1919.

Application filed April 23, 1918. Serial No. 230,332.

To all whom it may concern:

Be it known that I, WILLIAM F. SHAW, a citizen of the United States, residing at Pueblo, in the county of Pueblo and State of Colorado, have invented a new and useful Artificial-Tooth Attachment, of which the following is a specification.

It is one object of the present invention to provide novel means for holding an artificial denture in place. Another object of the invention is to provide novel means whereby a facing may be held on a structure which is to be assembled with the root of a natural tooth.

15 It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that, within 25 in the scope of what is claimed, changes in the precise embodiment of the invention shown can be made without departing from the spirit of the invention.

In the drawings:—

30 Figure 1 shows inside elevation, one form of the invention, assembled with a portion of a tooth, the latter being shown in section; Fig. 2 is a longitudinal section of the structure shown in Fig. 1, parts being shown in 35 elevation, and the root of the tooth being omitted; Fig. 3 is a cross section on the line 3—3 of Fig. 2; Fig. 4 is a cross section on the line 4—4 of Fig. 2; Fig. 5 is a composite perspective view, wherein the parts of 40 the structure shown in Figs. 1 and 2 are depicted in spaced relation; and Fig. 6 is a sectional view showing slight modification in the invention.

In carrying out the invention as disclosed 45 in Figs. 1 to 5, there is provided a hollow pin 1 made of malleable metal, the pin being slit longitudinally as shown at "1^a" and being grooved or milled on its edges as shown at 2 and including a flat wing 3 having an opening 4. The numeral 5 marks a disk of 50 malleable metal having an opening 20. At 6 there appears a backing plate of malleable metal provided at its ends with laterally inclined flanges 7 and 8, the backing plate 55 having an opening 9.

A T-shaped anchor 10 is provided, the

same being made of malleable metal and including a head 11 having an opening 12, and a shank 14, the shank being bifurcated to form bendable prongs 15. In the ends of the 60 head 11, anchoring notches 16 are formed. The numeral 17 marks a facing which may be made of porcelain, the facing having a longitudinal under cut recess 18.

In practical operation, a drill hole 21 is 65 fashioned in the root of a tooth 22. The pin 1 is inserted through the opening 20 in the disk 5, and is mounted in the drill hole 21. A slender instrument is inserted within the pin 1 and the same is burnished to conform 70 closely to the drill hole 21, the disk 5 being burnished down on the end of the root 22. The prongs 15 of the anchor 10 pass through the opening 9 in the backing plate 6 and through the opening 4 in the wing 75 3 of the pin 1, the prongs being clenched down on the wing 3, to hold the parts 6 and 3 together. The head 11 of the anchor 10 is received in the under cut recess 18 of the facing 17, the flange 7 of the backing 80 plate 6 engaging the base of the facing 17, and the flange 8 engaging the exposed end of the facing to form a biting tip, all of the parts being, of course, properly shaped. The head 11 is held in the recess 18 of the 85 facing 17, by cement indicated at 23, the cement finding an anchorage in the opening 12 and in the notches 16. The structure, having been assembled, is invested, and a mass of solder indicated at 19 is connected 90 with the backing plate 6, the wing 3 and the disk 5, the structure being burnished and finished up. The pin 1 now may be inserted into the drill hole 21 of the root and be held there by cement indicated at 24, the cement engaging the grooved or milled part 2 95 of the pin 1.

In Fig. 6, a slight modification of the invention is shown.

In Fig. 6, the hollow pin is of the sort 100 hereinbefore described, and is denoted by the numeral 25, the grooves or milling being shown at 26. The pin includes a head 27 having an opening 28, there being a flange or rib 29 at the point of juncture between 105 the head 27 and the pin 25. The numeral 30 denotes an artificial tooth having an under cut recess 31 and provided with a counterbore 32 at the base of the recess. The head 27 of the pin is received in the recess 110 31 and is held therein by cement shown at 50, the cement finding an anchorage in the

opening 28, the rib 29 being received in the counterbore 32.

The particular method of using or applying the structure shown in Fig. 6 will be clearly understood from what has been said hereinbefore concerning that form of the invention which is disclosed in the preceding figures. In general, the specific procedure outlined may be departed from without jeopardizing the utility of the invention.

Reverting to that form of the invention which is shown in Fig. 1, it will be understood that if the facing 17 should become broken, a new facing can be fitted in place without removing the remaining parts of the device from the root of the tooth. The hollow pin 1, or the pin 25, is so constructed to fit the bore or drill hole. Further, if it becomes necessary to remove the pin 1, a tool may be run up inside of the pin for this purpose. The facing 17 is beveled as shown at 34 to receive the flanges 7 and 8 of the backing plate 6 and since the flanges 7 and 8 diverge as shown in the drawings, the facing 17 may be replaced readily when required.

Having thus described the invention, what is claimed is:—

30 1. As an article of manufacture, a hollow longitudinally split denture-pin made of malleable metal, the pin being provided ad-

jacent its longitudinal edges with external cement receiving recesses.

2. In a device of the class described, a pin 35 having a wing provided with an opening; a backing plate coöperating with the wing and having an opening; a facing coöperating with the backing plate; and an anchor assembled with the facing and having a bendable 40 prong passing through the openings and clenched on the wing.

3. In a device of the class described, a facing having beveled ends; a backing plate provided with flanges coöperating with the 45 beveled ends of the facing, one flange forming a biting tip; a pin having a wing; and an anchor assembled with the facing and passing through the backing plate, the anchor engaging the wing of the pin.

4. As an article of manufacture, a denture pin made of malleable metal, whereby the pin may be shaped from its interior to conform to the bore wherein the pin is received, the pin being hollow and being slit 55 longitudinally, to form an opening of appreciable width for the reception of cement.

In testimony that I claim the foregoing as my own, I have hereto affixed my signature in the presence of two witnesses.

WILLIAM F. SHAW.
